UNITED STATES PATENT OFFICE.

JOHN KNOX RICHIE, OF LOS ANGELES, CALIFORNIA.

DESIGN FOR A SMOKER'S STAND.

Application filed February 17, 1928. Serial No. 25,472. Term of patent 3½ years.

To all whom it may concern:

Be it known that I, JOHN KNOX RICHIE, a citizen of the United States, residing at Los Angeles, in the county of Los Angeles and State of California, have invented a new, original, and ornamental Design for a Smoker's Stand, of which the following is a specification, reference being had to the accompanying drawing, forming part thereof.

I claim:

The ornamental design for a smoker's stand, as shown.

JOHN KNOX RICHIE.
